UNITED STATES PATENT OFFICE.

JOHN COOK ST. CLAIR, OF JOHNSTOWN, PENNSYLVANIA.

WIRE-ANNEALING FURNACE.

1,269,973.

Specification of Letters Patent. Patented June 18, 1918.

Application filed November 2, 1917. Serial No. 199,990.

To all whom it may concern:

Be it known that I, JOHN COOK ST. CLAIR, a citizen of the United States, residing at Johnstown, in the county of Cambria and

5 State of Pennsylvania, have invented a Wire-Annealing Furnace, of which the following is a specification.

Figure 1 is a side elevation. Fig. 2 is front elevation. Fig. 3 is side elevation with 10 outer brick wall removed. Fig. 4 is rear elevation. Fig. 5 is a view in elevation of one of the sheaves as herein embodied.

1—1 are cooling doors to be used in regulating temperature of the heat chamber 5. 15 2—2 are doors of fire boxes 9—9. 3—3 are doors to admit arms 6 upon which are sheave wheels 7, around which the wire is wrapped, the number of wraps determines the extent of annealation.

20 Arms 6 are drawn singly from the furnace to allow wire to be wrapped around sheaves 7, after which sheaves and arms are returned to furnace.

The wire continues from sheaves through 25 holes in perforated plate 4, and is drawn from furnace by machinery working independently of furnace.

10 is rod upon which are secured jointed arms 6. 11 is a solid brick wall between 30 fire compartment 8 and heat chamber 5. 12 is a brick or metal arrangement upon which rests arms 6 and keeps sheaves 7 slightly elevated above floor of heat chamber 5.

13 is draft route leading from fire compartment to under-ground flue.

I might add the following information concerning my invention:

While my drawing shows thirty arms and sheaves, this particular number does not in 40 any way enter into the ideas embodied in my invention. The number of arms and sheaves may be more or less than shown in my drawing.

The arms holding the sheaves are so arranged that they can be drawn singly from the furnace, the wire is then wrapped around the sheaves, the number of wraps will determine the extent of annealation; for instance, a strand of wire given ten 45 wraps around a sheave will not be annealed to the same degree of softness as a strand of wire given twenty wraps, for the reason that the strand of wire given twenty wraps will remain in the furnace twice as long as the strand given ten wraps.

I will also add that a particular size of

furnace, or in fact, a particular size of any part of the furnace does not enter into the ideas embodied in my invention.

I am aware that prior to my invention the 60 lead-pan method of annealing wire was used, but this being entirely different from my invention, I claim:

1. In a wire annealing furnace having openings in one end, a series of sheaves 65 supported on jointed arms adapted to be individually withdrawn or placed into the furnace chamber through said openings, and perforations in line with said openings at the other end through which the wire is 70 drawn from the furnace.

2. In a wire annealing furnace having an opening in one wall, a sheave supported on a jointed arm adapted to be withdrawn or placed into the furnace chamber through 75 said opening, a wall of the furnace chamber being provided with a perforation through which the wire is drawn from the furnace.

3. In a wire annealing furnace having an 80 opening in one wall, a sheave supported on a jointed arm adapted to be withdrawn or placed into the furnace chamber through said opening, a wall of the furnace chamber being provided with a perforation through 85 which the wire is drawn from the furnace, and means coacting with the portion of the arm inserted within the furnace chamber for maintaining the sheave carried thereby out of contact with the floor of the furnace 90 chamber.

4. In a wire annealing furnace having openings in a wall of the furnace chamber, a series of sheaves supported on jointed arms adapted to be individually withdrawn 95 or placed into the furnace chamber through said openings, and perforations in a wall of the furnace chamber through which the wire is withdrawn from the furnace chamber.

5. A wire annealing furnace having openings in the wall of the furnace chamber, a sheave supported on a jointed arm adapted to be withdrawn or placed into the furnace chamber through said openings, an end portion of said jointed arm being pivotally mounted exteriorly of the furnace at a point below the opening, a wall of the furnace chamber being provided with a perforation through which the wire is drawn from the 105 furnace.

6. In a wire annealing furnace having an

opening in a wall of the furnace chamber, a sheave supported on an arm adapted to be withdrawn or placed into the furnace chamber through said opening, a wall of the furnace chamber being provided with a perforation through which the wire is drawn from the furnace.

7. In a wire annealing furnace having an opening in a wall of the furnace chamber, a sheave supported on an arm adapted to be

withdrawn or placed into the furnace chamber through said opening, a wall of the furnace chamber being provided with a perforation through which the wire is drawn from the furnace, and means coacting with the arm when inserted within the furnace chamber for maintaining the sheave carried thereby out of contact with the floor of the furnace chamber.

JOHN COOK ST. CLAIR.
